Primary Examiner — Samantha Wood*Assistant Examiner* — Vanessa Martinez(74) *Attorney, Agent, or Firm* — Vladimir Postnikov(57) **CLAIM**

The ornamental design for a gel tips lamp, as shown and described.

DESCRIPTION

FIG. 1 is a right side view of a gel tips lamp according to the invention;

FIG. 2 is a left side view of the gel tips lamp according to the invention;

FIG. 3 is a front view of the gel tips lamp according to the invention;

FIG. 4 is a back view of the gel tips lamp according to the invention;

FIG. 5 is a top view of the gel tips lamp according to the invention;

FIG. 6 is a bottom view of the gel tips lamp according to the invention; and,

FIG. 7 is a perspective view of the gel tips lamp according to the invention.

The broken lines are included for the purpose of illustrating portions of the article and form no part of the claimed design.

1 Claim, 7 Drawing Sheets(56)
